ATTORNEY

UNITED STATES PATENT OFFICE

138,189

DESIGN FOR A CUTTING TOOL

Lawson A. Smith, Los Angeles, Calif., assignor to Robert H. Clark, Los Angeles, Calif.

Application April 14, 1944, Serial No. 113,249

Term of patent 14 years

(Cl. D54—13)

To all whom it may concern:

Be it known that I, Lawson A. Smith, a citizen of the United States, residing in the city of Los Angeles, county of Los Angeles, and State of California, have invented a new, original, and ornamental Design for a Cutting Tool, of which the following is a specification, reference being had to the accompanying drawing, forming a part thereof.

Fig. 1 is a perspective view of the cutting tool showing my new design, and Fig. 2 is a bottom end view of the tool.

I claim:

The ornamental design for a cutting tool, as shown.

LAWSON A. SMITH.
